PRINTING MECHANISM FOR COMPUTING-MACHINES.

1,121,826.

Specification of Letters Patent. Patented Dec. 22, 1914.

Application filed May 28, 1914. Serial No. 841,552.

To all whom it may concern:

Be it known that I, JOHN EMIL WILLIAM GREVE, subject of the Emperor of Germany, residing at Chemnitz, Saxony, Germany, have invented certain new and useful Improvements in Printing Mechanism for Computing-Machines, of which the following is a specification.

This invention relates to printing mechanism for computing machines, and has for its purpose to produce an organization which provides that the releasing-devices for the printing hammers, which, in known arrangements, stand normally under the pressure of springs, shall be normally relieved from this pressure and are only brought under the spring pressure, when the progress of the work demands, that is, when those releasing-devices are returned, which correspond to the type-bars which are not selected for printing, whereby they are positively withheld from extending into the range of action of the actuating-mechanism which sets in operation the remaining release-devices. In this manner it is prevented, that releasing devices, which belong to type-bars of the banks in which the zeros should not make an impression, will be carried along either through friction, bad positioning of the machine or vibration, and set in operation from the descending actuating-mechanism.

One form of the subject-matter of the invention is shown in the accompanying drawings, in which,

Figure 1 is a side elevation of the printing-mechanism with locked printing hammers and freed releasing devices, and Fig. 2 shows the position of the printing hammers and springs of the releasing devices together with the position of the latter when a number is being printed. Fig. 3 is a rear elevation of the mechanism, Fig. 4 is a plan view, and Fig. 5 is a horizontal section on line 5--5 of Fig. 1.

The type-bars 126 carry in well-known manner spring pressed sets of type figures from 0 to 9, and are provided at their lower ends with racks, by means of which they are set through the medium of a well-known mechanism, to a position corresponding with the keys depressed on the key-board, not shown herein, but which are shown and described in my pending application for

Patent Serial No. 716,480, filed August 22, 1912.

The printing hammers 128 are all arranged on a common axis 128^a and are held in their inoperative positions by means of two-armed levers 129, which are pivotally mounted on the shaft 140 and are provided with locking pawls 129^b adapted to engage with corresponding hook-members 129^b formed on the printing hammers. On the free arms of the two-armed levers 129 are suspended the releasing-rods 132, said release-rods having projections 132^c suitably provided with anti-friction rollers which engage the recesses 131 formed in the type-bars 126, said recesses 131 having inclined sides to permit the sliding engagement and disengagement therewith of the projections 132^c. On a fixed part of the machine, as for example, upon the frame 141 which supports the assembled printing mechanism, is pivotally mounted a yoke 142 upon the stub 143, said yoke 142 having on its side elements the projecting lever-arms 144, to which are pivotally joined, one at each side, the toggle-link connections 145, 146, the links 146 having pivotal connections with the carrier-frame 141 of the printing-mechanism by means of stubs or screw-shafts 147. The yoke 142 is provided with a housing 148 mounted on its connecting cross-bar, in which the spring-pressed pins 149 are arranged, said pins being normally projected from the housing under action of the springs but being adapted to be pushed therein in contact with the release-bars 132. Both toggle-connections 145, 146 are adapted to be actuated by pins 150 carried by the swinging levers 151 and 151^b which are mounted to rotate on a shaft 157 carried by the frame 141, said connections being limited in their movements by the stop-pins 152 and 153. The elements 146 of the toggle-connections 145, 146 are provided with projections 154, one of which co-operates with a lug 155 formed on the end of a draw-bar 156 which is operated by a hand-lever (not shown) and the other of which co-operates with a striking-pin 151^c mounted on a swinging-lever 151^b upon the shaft 157.

The draw-bar 156 is pivotally connected by means of the pin 156^a with the depending projection of the swinging lever 151, upon whose rotating shaft 157 there is also

mounted a freely rotatable lever 158, said lever 158 being adapted to coöperate with the actuating-yoke 159 for the release-bars 132. This actuating yoke 159 operates in a 5 guide-slot 160 (Fig. 2) formed in a projecting portion 161 of the frame 141 and is normally held in elevated position by means of spiral springs 163. Upon the shaft 157 is also mounted further a lever 164, which 10 carries a friction-roller 165 engaging in turn in the forked ends of the two-armed reciprocating lever 167 fixed on the shaft 166. The arms 168 of the levers 167 are connected by means of links 169 with the 15 bell-crank levers 170, 171, which are secured upon the shaft 128^a. A transverse bar 128^c, extending over the printing hammers 126 connects the arms 171 of the bell-crank levers 170, 171, so that the duplicate sets of 20 levers operate together.

The operation of the above described mechanism is as follows: At the beginning of the forward movement of the hand crank, the draw-bar 156 is moved in the direction of 25 the arrow in Fig. 1 by means of a transfer mechanism of well-known construction, and swings the lever 151 upon the shaft 157, and at the same time actuates levers 151^a and 151^b, which are also secured in the 30 shaft 157, in a counter clockwise direction. The pins 150 carried by the levers 151 and 151^b swing into engagement with the toggle connections 145, 146 and depress them into 35 extended position. When said toggles are thus extended, the pin 150 should have been brought into a position of engagement with the lever 158 and pushed the latter downward to the position shown in Fig. 2. By 40 the depression of the toggle connections 145, 146 the carrier-yoke 142 for the spring actuated pins 149 is turned to the right (Figs. 1 and 2) on its pivot-pins 143 and comes into a position against the release-bars 132. By 45 means of the downward movement of the lever 158 the yoke 159 is carried vertically downward in its guides 160 against the action of the springs 163. During the time of idle movement of the pins 150, the type-bars 126 are raised in a well-known 50 manner, and by means of the reaction of the cam sides of the recesses 131 on the projection 132^a the release-bars 132 are swung outwardly on their pivot-pins on the two-armed levers 129, so that the projections 55 132^a engage below the draw-yoke 159, and can be carried along by the latter. When the release-bars 132 are thus actuated, then they release by means of the lever 129 in a 60 manner also well-known the printing hammers 128. It is evident, that since during the meanwhile upward movement of the type-bars, the pins 150 execute an idle movement and then only at the end of this 65 movement depress the toggle 145, 146, the release bars 132 and the type-bars are not

actuated, but are free to move upwardly, so that the contact, which is occasioned through a well-known mechanism as heretofore used and is maintained by the constant pressure of leaf-springs on the release bars 132, will be avoided, a condition, which makes itself advantageously noticeable in the present apparatus particularly in the operation of multiple-bank machines. When the spring-actuated bolts 149 are pressed into position 70 against the release-bars 132, through the medium of the carrier-yoke 142, after the depression of the toggle 145, 146, they exercise two separate operations. Namely, if in any case the release bars should happen to be set into outer position through any undesired action, as by friction, improper positioning of the machine, or through vibration, so that they are liable to be locked to the draw-yoke 159, then the resistance 75 of the spring-pressed bolts 149 returns those release-bars 132 which are in obviously wrong position back to proper position, so that in this way the release-bars are regulated by the spring-actuated bolts. The release-bars which are properly outwardly 80 swung or set, and which release the corresponding printing hammers in order to print the number set up on the key-board, stand, as shown in Fig. 2, during the operation 85 of the yoke 159 under the pressure of the spring-pressed bolts 149, so that after the printing of the number, when all of the other elements have been returned to their normal positions, the spring-pressed bolts 90 exercise their second function, in that, they permit that the release-bars also return to their normal positions when the type-bars 95 100 descend and the projections on the release-bars return to the recesses 131. 105

When the parts of the computing-machine carry out the return movements to the position of rest, then the draw-bar 156 moves to the left and turns thereby the lever 151, 151^a, 151^b and 164 in the clockwise direction. The nose or lug 155 on bar 156 on one side of the machine strikes against the projection or arm 154 and the pin 151^c on lever 151^a on the other side of the machine strikes 110 against arm 154 of the corresponding toggle-connection, whereby the toggle-lever is returned to its accustomed position according to Fig. 1. At the return of pin 150 the lever 158 and the yoke 159 are set free, so that the springs 163 operate to return the latter element to normal position. When the lever 164 swings back the forked-lever 167 is 115 swung upwardly to the right and turns, through the medium of the shaft 166, the lever-arm 168 downwardly to the left, whereby the latter, by means of the pivoted-link 169 on the bell-crank lever 170, 171, turns with its shaft 128^a in a clock-wise direction and the cross-bar 128^c presses back 120 the released printing hammers until they 125 130

snap under the lugs 129^a of the lock-levers 129. In this manner all of the elements are returned to their normal position.

What I claim is:—

- 5 1. Printing mechanism for computing machines, comprising in combination, a plurality of type-bars, spring-actuated printing hammers for said type-bars, means for normally locking said hammers against spring-pressure, a series of release-bars for releasing said hammers, means to actuate said release bars, and a resistant means to be drawn into contact with said release-bars to regulate the setting of the latter.
- 10 2. Printing mechanism for computing machines, comprising in combination, a plurality of type-bars, spring-actuated printing hammers for said type-bars, means for normally locking said hammers against spring-pressure, a series of release-bars for releasing said hammers, means to actuate said release-bars, and a resistant means to be drawn into contact with said release-bars to regulate the setting of the latter.
- 15 3. Printing mechanism for computing machines, comprising in combination, a plurality of type-bars, spring-actuated printing hammers for said type-bars, means for normally locking said hammers against spring-pressure, a series of release-bars for releasing said hammers, means to actuate said release-bars, and a resistant means to be drawn into contact with said release-bars to regulate the setting of the latter.
- 20 4. Printing mechanism for computing machines, comprising in combination, a plurality of type-bars, spring-actuated printing hammers for said type-bars, means for normally locking said hammers against spring-pressure, a series of release-bars for releasing said hammers, means to actuate said release-bars, and a resistant means to be drawn into contact with said release-bars to regulate the setting of the latter.
- 25 5. Printing mechanism for computing machines, comprising in combination, a plurality of type-bars, spring-actuated printing hammers for said type-bars, means for normally locking said hammers against spring-pressure, a series of release-bars for releasing said hammers, means to actuate said release-bars, and a resistant means to be drawn into contact with said release-bars to regulate the setting of the latter.

pressure, a series of release-bars for releasing said hammers, means to actuate said release-bars, a resilient means adapted to be 35 removably carried into engagement with said release-bars to control the movement of the latter after their setting, a yoke carrying said bolts for simultaneous movement, and means to actuate said yoke.

40 4. Printing mechanism for computing machines, comprising in combination, a plurality of type-bars, spring-actuated printing hammers for said type-bars, means for normally locking said hammers against spring-pressure, a series of release-bars for releasing said hammer, means to actuate said release-bars, a resilient means adapted to be 45 removably carried into engagement with said release-bars to control the movement of the latter after their setting, a yoke carrying said bolts for simultaneous movement, a toggle connection between said yoke and said release-bar actuating means and means for extending said toggle-connection to actuate 50 said yoke simultaneously with the actuation of said release-bar actuating means.

45 In testimony whereof I affix my signature in presence of two witnesses.

JOHN EMIL WILLIAM GREVE.
